UNITED STATES PATENT OFFICE.

LOUIS BINDER, OF NEWARK, NEW JERSEY.

BOX.

1,277,536.

Specification of Letters Patent.

Patented Sept. 3, 1918.

Application filed April 8, 1918. Serial No. 227,194.

To all whom it may concern:

Be it known that I, LOUIS BINDER, a citizen of the United States, and a resident of Newark, county of Essex, and State of New Jersey, have invented certain new and useful Improvements in Boxes, of which the following is a specification.

My invention relates to boxes and has for its object the improvement of articles of this character in a number of important respects as will appear in detail below. With this object in view, my invention consists in the improvements, features of construction, combinations and processes hereinafter described and claimed.

In the accompanying drawing forming part of this specification, and wherein the same reference numerals are uniformly used to designate the same parts throughout, Figure 1 is a perspective view of a box embodying one form of my invention with its lid closed. Fig. 2 is a fragmentary, perspective, detail view of one of the upper corners of the box body. Fig. 3 is a similar view and illustrating a bottom corner of the box body. Fig. 4 is a fragmentary perspective view of one corner of the cover. Fig. 5 is a fragmentary perspective view illustrating an upper corner of the box body and one corner of the lid in place thereon. Fig. 6 is a bottom plan view of a box blank with the sides and ends bent downwardly. Fig. 7 is a fragmentary perspective and part cross-sectional view illustrating one step in the process of formation of the box from a blank. Fig. 8 is a cross-sectional view illustrating a further step in the formation of a box. Fig. 9 is a plan view showing the relation between the side and end walls of the box after it has been formed up, and Fig. 10 is a cross-sectional view showing the relation of the lid to the box body when closed.

The blank from which the principal portion of the box is formed is designated by reference numeral 10. Its corners are cut out in substantially the usual way, but with provision for the assembly of the box so as to obtain flush corners, as hereinafter described. The side walls are indicated by the reference numerals 11, 11 and an end wall by the numeral 12. The box blank, which is preferably of pasteboard or heavy cardboard or the like, is slitted almost through about the outline of the bottom 13, as illustrated at 14, 14, Fig. 6, leaving a substantially square cornered recess 15 (as illus-

trated in Fig. 7), when the sides 11 and ends 12 are turned to positions substantially at right angles to the bottom 13. Similar results may also be secured by cutting the bottom clear through and providing a sheet of paper, fabric or the like on the interior to keep the parts in proper positions, but preferably the blank is slitted quite deeply, as illustrated, but not quite entirely through. If the box were left in the form shown in Fig. 7 there would, of course, be substantially open grooves along the corners and angles thereof, and in order to obtain substantially square and perfect corners the parts are forcibly pressed inwardly with respect to one another, as, for example, the bottom 13 may be forced inwardly with respect to the side wall 11, as clearly shown in Fig. 8, so that the under surface 13' of the bottom 13 (inverted as in Fig. 8) is flush with the adjacent edge 11' of the side wall 11, and also, of course, the same relation is had with the end walls 12. This result may be secured in any suitable way, as, for example, dies A, B, C may be used for bringing the parts into the desired relative positions, glue, cement or the like, as indicated by the numeral 16, being preferably applied before the parts are brought together, as illustrated in Fig. 8. It will be observed that the bottom 13 remains attached to the side and end walls by the uncut material 17 as well as being secured thereto by means of the glue or other cementitious material 16, and in this way a satisfactory and substantial joint is obtained and at the same time the corners are flush and squared, and when the box is covered with the outer sheet of paper 18 or the like, as is customary, a square edge is formed, all the angles of the box giving a very neat and satisfactory appearance, and at the same time a box of substantial strength is obtained. The end walls 12 and side walls 11 are brought together as clearly shown in Fig. 9, and in cutting out the corners of the blank 10 the side members 11 may be extended at their ends 11'', 11'', as illustrated in Fig. 6, so that when the side and end members are brought into their permanent positions with respect to one another there is sufficient material in the side walls 11 to extend over and complete the corner where joined to the end walls 12, as clearly shown in Figs. 6 and 9.

A box having its outer walls and bottom

constructed in the manner described affords a structure having sharp, well defined corners and a pleasing exterior, and boxes so constructed and having but one wall and bottom thickness may be utilized in accordance with the invention, but preferably, and particularly where boxes are desired to replace the expensive wooden boxes now used for cigars and similar articles, a somewhat greater thickness of wall is desirable than can be conveniently obtained with a single thickness of material. Also by the use of side and end walls comprising several thicknesses of material it becomes possible to secure a desirable frictional holding effect for the lid, as will be hereinafter referred to. I preferably make use of side and end walls having three thicknesses of material, as is shown in Fig. 3, and including the outer wall 11, an inner wall member 19 and an intermediate wall member 20. The intermediate wall member 20 may be narrower than the other walls and may terminate at its upper edge somewhat below the upper surface of the box sides and ends, as illustrated in Fig. 2, providing an intermediate channel 21 for the reception of a suitably formed flange with which the lid may be provided. Also the inner wall 19 may terminate somewhat below the outer wall 11, as illustrated in Fig. 5, and this construction is preferably utilized in connection with a lid suitably formed to coöperate therewith.

A lid of desirable construction for use in connection with such three-thickness wall section is illustrated in Figs. 4 and 5, in which the lid is designated generally by the reference numeral 22, and the outer thickness of cardboard or the like material 23, an intermediate thickness of such material by reference numeral 24, and the inner portion by the numeral 25. These parts are preferably each successively somewhat smaller than one another in the order named. The inner part 25 is preferably of such form and shape as that its edges 26, 26, fit fairly closely within and against the edges of the inner wall members 19, 19. The intermediate portion 24 preferably projects outwardly somewhat farther than the portion 25 and is provided with a flange 27 adapted to fit within the channel 21 between the side wall members and leaving a shallow channel 28 of a width to receive the upper edges of the wall members 19, 19. The outer lid member 23 is preferably formed with a flange 29 around all its sides but the back thereof, where the hinge 30 is secured, and this flange 29 preferably embraces the outer wall portions 11, as shown clearly in Figs. 1 and 3, the upper edge of the wall portions 11 being received within the channel 28 between the flanges 29 and 27. The reason for making the wall portions 19 slightly narrower than the outer

wall portions 11 will now be apparent, the difference in height between such portions 11 and 19 being substantially that corresponding to the thickness of the intermediate portion 24 of the cover, and the upper edge of the portion 19, when the lid is closed, coming substantially in contact with that portion of the intermediate cover part 24 which forms the base of the groove 28. The hinge member 30, which is preferably of flexible material, as fabric or the like, affords a comparatively loose hinging support for the lid 22 upon the box body, so that the same may adapt itself to fit the body, and the hinge member 30 may be secured in place as by being glued or cemented between the plies of the walls and body members, as clearly shown in Fig. 5.

It will be seen that when the lid is closed, a very efficient frictional holding effect is obtained, the flanges and channels of the lid coöperating with the edges and channels of the upper portion of the box body, which are substantially nested together, and all the parts are in substantially close contact. While the parts may be readily made so as to fit together, there are always more or less small inaccuracies in the relative sizes and proportions, and the box body always has more or less tendency to skew slightly out of shape, so that upon closing the lid and pushing it shut a frictional binding or holding effect is secured, and the lid is tightly held closed by friction, but nevertheless the parts have such degree of flexibility that the lid can readily be opened by means of such force as can be applied by the thumb or finger. The box bottom may be reënforced, if desired, but a single thickness is usually sufficient for ordinary purposes, and it is so illustrated in Fig. 3 of the drawing.

It will be seen that a box in accordance with the invention presents a number of features of advantage. Sharp, well defined corners and edges are obtained in a very simple and effective manner, the box is of simple and cheap construction and the interlocking arrangement between the lid and the body walls assures that the box, when closed, will remain closed, but it can be opened by the exertion of a small amount of force for that purpose when desired. When the box is closed its contents are thoroughly protected, the interlocking obtained between the box being of such character as to act substantially as an air-tight seal so that evaporation of moisture, for example, in goods such as cigars is substantially prevented.

I claim:

1. In a box, a box body having a groove in its upper edge, and a box lid hinged thereto and having a flange adapted to enter said groove, and a second flange

- adapted to fit over the exterior of the body wall.
2. In a box, a box body having walls provided with a groove therebetween, the inner wall being of less height than the outer wall, and a lid adapted to fit on said body and provided with flanges to enter said groove and to fit outside the wall, respectively, and also being provided with channelled portions to receive the upper edges of the inner and outer portions of the body walls.
3. In a box, a box body having walls comprising three wall members, the intermediate one of said members being narrower than the other two, and a lid likewise comprised of three-ply thicknesses, the intermediate ply having a flange adapted to be received within the channel between the inner and outer members of the wall body. 15
- 20

In testimony that I claim the foregoing, I have hereto set my hand, this 5th day of April, 1918.

LOUIS BINDER.
